CONSTRUCTION ELEMENT

Augustine Davis, Jr., Cincinnati, Ohio

Application September 17, 1936, Serial No. 101,280

6 Claims. (Cl. 189—40)

This invention relates to improvements in a construction element particularly to a composite element to take the place of floor beams, or joists, wall studs, roof rafters, headers and the similar parts used in building construction.

Here-to-fore, attempts have been made to produce a construction element which were composite in their nature, that is, formed partly of metal and partly of wood, or other comparatively soft material, thereby affording means that may readily be nailed to. Other attempts to replace the wood construction member of buildings have been made, by specially forming a metallic member and then utilizing special connecting parts for securing the construction elements to one another. In each of these instances certain difficulties have been encountered either in that the construction element had sides which were provided with flanges and thereby could not be very readily substituted for the wooden member, or else specially trained erectors were needed for erecting the all metal element by means of the special connectors. By this invention, there is provided a construction element, as above noted, which can be readily fabricated by a carpenter or building erector without difficulty while, at the same time, having a building construction which is considerably stronger and very favorably compares with all metal buildings.

It is, therefore, one of the principal objects of the present invention to provide an efficient building element or construction element which is comparatively simple and economical to manufacture, economical to use and readily substituted for the construction element now employed, and not requiring a special trained erector therefor.

Another object of this invention is the provision of a building or construction element, which is formed of metal and wood, that can readily be assembled, and in which the said elements can readily be connected to one another.

A further object of this invention is the provision of a construction element, so formed that a light gauge material may be employed, without sacrificing strength and rigidity, and in which the most efficient use and distribution of the metal is obtained.

It is also an object of this invention to provide a housing structure in which the elements thereof may be temporarily secured together by carpenters, and the like, and later permanently connected by a permanently uniting means, such as welding, etc.

A still further object of this invention is the provision of a housing structure in which the parts are so connected to one another, that certain elements thereof are primarily under tensile strain, whereby considerably lighter gauge material may be employed, with safety, in the structural elements and, thereby, materially lessening the dead load in the frame, and economically distributing the whole load.

Other objects and advantages of the present invention should be readily apparent by reference to the following specification considered in conjunction with the accompanying drawings forming a part thereof, and it is to be understood that any modifications may be made in the exact structural details there shown and described, within the scope of the appended claims, without departing from or exceeding the spirit of the invention.

In the drawings:

Fig. 1 is a perspective, fragmentary view of a construction element, embodying the features and improvements of this invention.

Fig. 2 is a perspective, fragmentary view of one of the side members of the construction element shown in Fig. 1.

Fig. 3 is a sectional view through the construction element, as seen from line 3—3 of Fig. 1.

Fig. 4 is a cross, sectional view, similar to Fig. 3, but showing a slight modification in the construction.

Fig. 5 is a fragmentary, perspective view of a construction element, somewhat narrower than that illustrated in Fig. 1, and utilized in practice, as a wall stud or roof rafter, while that of Fig. 1 is utilized for a floor beam or joist.

Fig. 6 is a section view taken on line 6—6 of Fig. 5.

Fig. 7 is a view, illustrating in perspective, the assembling of the construction elements of this invention.

Fig. 8 is a vertical, sectional view taken on line 8—8 of Fig. 7.

Fig. 9 is a perspective view of a section of a cap channel, utilized in the assembling of the construction elements of this invention, and forming a detail thereof.

Fig. 10 is an example of the utilization of the construction element of this invention for forming offset roof corners, gables, and the like; this view being on a smaller scale than that utilized in the other views.

Figs. 11 and 12 are fragmentary, perspective views of two different types of cornice construc-

tions, each utilizing the construction element of this invention.

Fig. 13 is a cross, sectional elevation of a dwelling house frame, utilizing the construction of this invention; and

Fig. 14 is a fragmentary view, illustrating the side joining of two construction elements of this invention.

Throughout the several views of the drawings, 10 similar reference characters are employed to denote the same or similar parts.

The construction element of this invention comprises a pair of correspondingly bent and shaped side members 15 and 16. Between these members, at the upper and lower sides thereof, are placed, nailing strips 17 and 18. In use, the width of the construction element is varied, depending upon the place in the building it is used. As shown in Figs. 1 to 4 inclusive, the depth of the construction element would be around 8" and of a width slightly less than 2", and may be utilized as a floor beam or joist. Under test, it has been found, that this beam or joist will bear a greater load than the wooden beam or joist, here-to-fore used, which was one half again as deep, such as the usual 2" x 12" (so called) wood planks, used for floor beams, joists, and the like. The overall length of these beams is of course variable, depending upon the span. If the said construction element is to be used for a wall stud, its thickness would substantially be the same as that pointed out, that is, a little under 2", while the width or depth thereof would be a little less than 4", to take the place of the usual 2" x 4" stud, 35 usually employed in a wall structure. Again, ceiling rafters are frequently formed of planks or boards having the rough measurement of 2" thick by 6" wide or deep, and the construction element of this invention, which would take their 40 place, could be of a corresponding dimension, but would probably be of less depth, due to its greater load capacity.

The side members 15 and 16, of the construction element, are identical and it is deemed sufficient if but one of them is described in detail, which is illustrated in Fig. 2. As seen in Fig. 2, the side member 15 is formed of a single piece of metal, providing a vertical wall or body portion 19, which is of a dimension equal to the total 45 depth or width of the construction element. At opposite edges of the body portion, the metal is folded upon itself to provide flanges 20 and 21, which are double to gauge or thickness of the sheet. Extending from the edge flanges toward 50 one another, the sheet is folded against the body portion, as at 22 and 23, and then the free edges of the sheet are folded normal to the portions 22 and 23, to provide the internal flanges 24 and 25. It is not absolutely necessary, but frequently 55 desirable, to insure that the parts at the bends do not separate and, therefore, the portions 22 and 23 may be respectively secured to the body portion by a series of spot welds 26 and 27, which extend the full length of the side members. The 60 body portion 19, of said side member, is provided at spaced intervals throughout its length, and between the internal flanges 24 and 25, with apertures 28 which, in the assembled construction element, are utilized for stringing pipes, 65 ducts, wires and the like. At least one of said openings such as 28', nearest one end of the construction element, is made larger than the others and preferably rectangular in shape to provide space for the usual hot air heating pipes to pass 70 therethrough. To insure sufficient rigidity at this

point, the said enlarged opening is re-enforced by a liner 29' passing therethrough.

The side members are then positioned in opposition to one another with the edge flanges 20 and 21 in given planes, and with the inner flanges 24 and 25 in planes intermediate the planes of the flanges 20 and 21. This arrangement provides a channel at the upper and lower, or inner and outer, sides of the construction element which is filled by a wooden strip or other relatively soft material. It will be appreciated that the strips 17 and 18 need not be continuous from end to end, but may be made up of random length, or relatively short, pieces, abutting one another. The width or lateral dimension of these strips 17 18 and 19 is greater than the combined width of the opposed flanges of the sides 15 and 16, whereby a space 29 is provided at the upper and lower, or inner and outer, sides of the construction element, between the flanges 20 and 21; and, since 20 the inner flanges 24 and 25 are normally longer than the outer flanges 20 and 21, there is provided a shorter space 30 between the said inner flanges 24 and 25 when the construction element is completely assembled. It should also be noted 25 that, as intimated above, the inserts 17 and 18, instead of being wood, may be formed of some resilient material such as a plastic, and molded to the desired dimension, or instead, the material, while in the plastic form, may be run into 30 the channels and allowed to set.

In order to hold the side members 15 and 16 in operative position, tie pieces 31 may be welded between the opposed flanges 20 and 21 after the inserts 17 and 18 are in position. These tie pieces 31 may take the form shown in Fig. 3, that is, be made of metal of a gauge equal to that of the metal from which the side members are formed, and will therefore be but half of the thickness of the flanges 20 and 21, and set below the outer 40 surface of said flanges. These tie pieces or strips are welded in position, as at 32 to insure that they remain in position. Instead of using inserted ties, as just described, the members may be secured to one another by tie pieces 31', as shown 45 in Fig. 8, in which case, the tie pieces are of a very light gauge of metal and mounted on the upper surfaces of the flanges 20 and 21 and welded thereto, as shown at 32'. This latter type of tie will not interfere with the subsequent 50 nailing to the construction element, since the gauge of the tie is insufficient to materially interfere with the flooring or the like, laid on the element. The sides 15 and 16 may be further secured to one another by small welds 33 which 55 connect the adjacent edges or ends of the inner flanges 24 and 25, as shown in Figs. 3 and 4. These small welds 33 are formed by inserting the welding tool through the apertures 28 and the 60 said welds will, therefore, be at the same intervals as the apertures 28. It has been found in practice, that the welds 33 are in themselves sufficient to hold the sides to one another, without using any tie plate, 31 or 31' on the outer flanges. Such a construction element is illustrated in 65 section in Fig. 4, and the invention is not, therefore, limited to the use of tie plates 31 or 31'.

The side members 15 and 16 are formed from relatively light gauge steel, such as from 12 to 24 gauge inclusive, the gauge, of course, depending 70 upon whether it is used as a floor beam or a wall stud or ceiling rafter and the amount of stress and strain to be placed thereon. These side members may be formed on a press brake, from sheet steel, or they may be pressed or rolled from 75

strip steel. If strip steel is employed, the inner flanges 24 and 25 may not be of uniform length since the edges of strip steel are not always uniform and the adjacent ends of these flanges, when in assembled form, may more or less, approach each other from that shown in the drawings. Should this spacing be greater than that required to make the inner welds 33, a short bridging piece, similar to 31 or 31', may be employed, to effect the tie of the internal flanges. The actual construction may even be further varied by spot welding this inner bridging piece to the flanges of one of the side members and after the construction element is assembled, the free end of the bridging piece welded to the flanges of the other side member, by inserting the welding tool through the aperture in the side member. It should also be noted at this time, that the side members may be joined to one another by means of welds bridging the space 29, in the same manner that the welds 33 bridge the space 30, and without using any tie pieces 31 or 31'.

The stud, illustrated in Figs. 5 and 6, is considerably narrower than that illustrated in Figs. 1 to 4, and is intended to be employed where a relatively narrow stud and the like is desired. This stud comprises a pair of side members 97 and 98, each having the longitudinal edge of the metal folded on itself to provide flanges 99 and 100, which are of double thickness and disposed at the longitudinal edges of the body portion 101. The side members 97 and 98 are arranged with their flanges in opposition to one another and are connected together, with a short space between them, either by a bridging piece, such as 31 or 31', or are connected together by welds, such as 33. This structure results in a tube, having a rectangular cross section and, disposed within this tube, is a resilient member 102, having a cross sectional area, substantially equal to the interior cross sectional area of the tube.

From the foregoing, it will now be appreciated that there has been provided, a composite structural element which is, in effect, a box girder. It will further be noted that this structural element is made up of one main box like girder having interiorly thereof, two additional box girders which is formed by the portions 22 and 23, and the flanges 20 and 24, and 21 and 25, respectively at the ends of the portions 22 and 23. It should also be noted that the metal in the side members is so arranged and proportioned, as to give the most efficient use thereof, since the body portions 19, of each of these side members is set on its edge to resist compression and, at the same time, are spaced the maximum distance from one another to give the maximum lateral rigidity to the element as a whole. This strength and rigidity results, even though the thickness or gauge of the metal is reduced to a minimum and has been found to resist deflection and withstand loads equal to, and greater than, other metallic construction elements which were formed of a considerably heavier gauge, and that the deflection in the construction element of this invention was well within the limits of safety, when placed under a greater load than that under which the wooden beam or joist failed.

Fig. 7 illustrates a method of assembly of a plurality of construction elements of this invention, together with a simple additional element for readily connecting the parts to one another. As shown in this figure, a plurality of floor beams, each floor beam being indicated as a whole by the

reference numeral 34, are mounted on a foundation wall or support 35. The beams 34 are then cross-braced by any well known method, such as a continuous band 36, which has its one end connected to the first floor beam at one end of the floor area, and passed below and above alternate successive beams, and the band having its other end secured to the last beam at the other end of the floor area. A second band 37 extends from beam to beam in opposite direction from that of the band 36, again passing alternately above and below successive beams.

Mounted on the upper surface of the beams, and transversely thereof at the point where the upright walls are to be, is a channel member 38, 15 shown in detail in Fig. 9. This channel member 38 comprises a bottom or base portion 40, having upturned flanges 41 and 42, at the opposite ends thereof. The bottom 40 and the flanges 41 and 42 are each provided with a plurality of perforations 20 43, spaced at convenient intervals, whereby said perforations will align with the nailing strips 17 and 18 of the beams and studding when mounted therein. It should be noted at this time that the width of the bottom or base 40 of the channel 38 25 is approximately equal to the width or depth of the construction element to be mounted therein.

The channel 38 is temporarily held in position on the beams 34 by driving a nail through the apertures in the bottom 40 into the upper nailing strip of the beams, whereupon the uprights or studs are placed in the channel. These uprights or studs are then temporarily held in position by driving a nail through the apertures in the sides 41 and 42 into the nailing strips at the 35 opposite sides thereof. Mounted on the upper ends of the uprights or joists is a second channel 44 which is identical with the channel 38 except that its position is inverted and may be referred as a cap channel for capping the upper ends of 40 the joist. This channel is again secured to the joist by driving nails through the apertured sides into the nailing strips of the joists. If there is to be a second floor to the building, the second floor beams or joists are mounted on the upper 45 surface of the cap channel 44. These second floor joists, each indicated as a whole by the reference numeral 45, have secured to them a U-shaped member 46 which is merely a short section of a channel, similar to the channels 38 and 44, but 50 being of a length equal to the width of the beam. Each of these connecting members 46, as seen in Fig. 7, comprises a base member 47, from which depend legs 48 and 49, which base member and legs are provided with one or more apertures. The base member 47, between the legs 48 and 49, is of a width equal to the entire width of the channel 44, so that said channel will fit between the legs 48 and 49. Previous to mounting the second floor beams on the channel 44, 60 the connecting members 46 were secured to each beam, as by nailing through the base thereof, and these parts are subsequently securely welded to each other, as by a series of short welds 56, at the edges of the bottom 47 of the connecting 65 member 46, where it contacts the flanges of the beam. By driving a nail through the registering apertures in the connecting member 46 and one side of the channel 44 into one of the nailing strips of the stud, the said second floor beam is 70 temporarily held in position. These floor beams may be suitably cross-braced by straps or bands, similar to the straps or bands 36 and 37, which brace the lower floor beams 34, as above described.

In order to provide openings in the upright 75

walls, as for doors, windows and the like, use is made of a section of a channel 51, which is identical with the channels 38 and 44. In order, however, to connect this channel at points intermediate the length of the joist, the sides 41 and 42 are cut from the base or bottom 40 for a distance equal to the thickness of the upright studding, thereby providing the arms 52 and 53, on the channel 51, see Figs. 7 and 8, which respectively lie on opposite sides of the upright or studding. The portion of the bottom cut from these sides is upset normal to the remaining portion of the bottom or base of the channel, as seen at 54, and lies against the inner side of the upright or stud, embraced by the arms 52 and 53. Again, by driving nails or the like through the apertures in the arms 52 and 53, these headers and foot channels may be temporarily held in position and subsequently have secured to them, the upper window frames, moldings, and window sills and the like parts. If desired of course, these channel sections 51 may have secured to them the usual wooden 2" x 4", or the like, to which in turn, the window casing, molding, trim and the like may be secured.

If desired, additional floors may be added to the building, in the same manner as above described, until the roof is reached, which, of course, terminates in a cap channel, similar to the cap channel 44. If it is desired to use the construction element of this invention for the floor beams only, and make the upright walls of wood construction members, as is the practice at this time, this can readily be done by nailing a plank to the nailing strips of the beams and secure by toe-nailing, or the like, the usual uprights, or the channel 38 could be secured to the beams, as above described, and a plank secured therein and the uprights secured to the plank, or the said uprights may be secured in position by nails, or the like, driven through the apertures in the channel flanges.

With the construction element of this invention, any type of roof may be made up with any desired overhang and eaves formation. Two of the more commoner types are illustrated in Figs. 11 and 12. As shown in Fig. 11, the roof channel 55 has the rafters 56 notched so that the outer ends of the rafters do not overhang the channel, but come vertically flush therewith. In Fig. 12, the opposite construction is illustrated, and shows the roof channel 55 with the rafters 56 so notched, that the lower ends 57, of each rafter, projects beyond the channel to provide an overhanging type of eaves. In each of these instances, the rafters may be temporarily held in position by light metal straps, or by board stringers, as in the usual wood construction, by nailing same to the rafter nailing strips or construction elements.

In Fig. 10, there is illustrated, the construction of a peaked offset of the roof, or a gable, in which the construction element of this invention is used. As shown in this view, the ridge piece 58 extends diagonally of the area of the roof corner and has extending therefrom the rafters 59 which extend to the cap channels 60 and 61. These members are temporarily secured in position by means of straps 62, each of which may connect the adjacent ends of the rafters to the ridge piece. A similar connecting piece 63 may be employed for connecting the outer ends of the rafters to the cap channel, or to the members 60 and 61, when they are made from the construction element of this invention. In this

connection, the wood stringers may also be used as is the usual practice with carpenters.

In Fig. 8, there is illustrated in phantom lines, an upright 64, which will form an extending portion of the building, such as a dormer window or the like. It will be noted from this illustration, that the construction element lends itself very readily for lateral or side engagement of one construction element with another construction element, in a manner very similar to that which is obtained from using the well known wood construction element. The said upright 64 may be temporarily mounted in position by driving nails up through the apertures in the base of the cap channel 44 into the ends of the nailing strips carried by the element, or a connecting strap, such as shown in phantom lines at 65, may be secured, by nailing the opposite ends thereof, respectively to the nailing strips of the adjacent elements. A further illustration of the side lapping of the construction element of this invention is disclosed in Fig. 14 in which it is desired to project one element normal to a second element. In this instance, the elements are temporarily held in position by the piece 66, which has its one end secured to the nailing strip of one element, and its other end secured to the nailing strip of the other element.

From the foregoing, it will now be appreciated that a complete building may be assembled by a carpenter, using nothing but carpenter's tools, with the exception, of course, of a metal saw for obtaining the angular cuts, where needed, of the composite structural element of this invention, since all of the parts are fit and nailed to one another right on the job. After the frame has been completely temporarily erected, as above described, a welder will go over the frame and run small welds at different points where the metal to metal contact is had between the different construction elements. These welds are indicated by the reference numeral 50, which reference character was above used to indicate the welds attaching the connecting element 46 to the second floor beam 45. After the various elements of the frame have been welded to one another, a very rigid frame results, each construction element of which has resilient nailing strips, whereby the outside weather boarding can be very readily secured in the same manner as heretofore employed and the inside trim and the like can be mounted in the same manner as now used. It should also be noted that plaster lath, either of the metallic or wood type, may be mounted in the same manner as heretofore, that is, by driving nails through the lath into the wood, or by driving a nail into the wood and bending the nail over the expanded metal lath, as is the usual practice.

In Fig. 13, is shown a cross-section of a completed residence or dwelling frame, built up of the construction elements of this invention, and illustrates the parts under tensile and compression stress, whereby the frame, in its final form, is to all intents and purposes, homogeneous. Specifically, this view illustrates the foundation walls 67 and 68 supporting the first floor beams or joists 69. These joists may or may not be supported from beneath by a support 70. Extending along the ends of the beams 69 and secured thereto, as above explained, are the channels 71 and 72, respectively supporting the uprights or studs 73 and 74 at each side of the building. These studs 73 and 74 are respectively capped by cap channels 75 and 76, on which is

5 mounted, in the manner above described, the second floor beams or joists 77. The second floor beams or joists carry, at their outer ends, respectively the channels 78 and 79 which, in turn, support the second floor uprights or studs 80 and 81. The third floor or attic floor beams and joists 82 are mounted on the second floor studs 80 and 81, in the same manner that the second floor beams and joists were mounted on the first floor studs.

10 The cap channels at the upper ends of the second floor studs, in addition to supporting the third floor or attic floor beams or joists, have connected thereto, the ends of the roof rafters 83 and 84, in a manner above described and illustrated in Figs. 11 and 12. The inner ends of the rafters 83 and 84 are angularly cut and butted against a ridge piece 85, which may be a strip of metal, or preferably formed of a construction element of this invention.

15 Mounted on the second floor beams or joists 77, and located intermediate the ends thereof, are the channels 86 and 87, respectively receiving the lower ends of the studs 88 and 89 of wall partitions. These wall partition's studs 88 and 89 are respectively capped by channels 90 and 91, which channels contact with the under surface of the third floor or attic floor beams or joists 82. Mounted on the upper surface of the 20 said joists 82, are channels 92 and 93 for the third floor partition studs 94 and 95. These third floor partition studs 94 and 95 are connected at the upper ends to a channel 96, which is formed at its opposite ends in the same manner that the header channel 51, above described, is formed, that is, is provided at its ends, with arms which embrace the sides of the rafters 83 and 84.

25 It will be noted that the second floor beams or joists are without support, except at the ends, which supports are the studding extending from the first floor. In the ordinary construction, this would mean that the weight on the beams or joists 77 would tend to bend these beams unless 30 they were unusually heavily constructed, thereby materially increasing the costs of the building, as well as materially adding to the dead load of the building.

35 With the construction element of this invention, and, formed as it is of comparatively light weight material and welded substantially at all parts of metallic contact, the elements are physically united, as much so, as if they were cast or rolled from a given piece. It is believed that 40 there will be no question raised as to the strength 45 of the welds, since it is well known that the joint where two relatively thin parts are welded to one another is stronger than the metal itself, and that in order to break the parts from one another, after they are welded, it is necessary 50 to tear one of the parts. From this, it then follows, that the second floor beams 77 need not be made any stronger than if they were 55 amply supported by studding and partitions underneath, since these beams are supported and suspended from the roof, which is in turn, supported by the studs 74 and 81 of both the first and second floors, and these studs are, in turn, braced against buckling by the cross beams or 60 joists 71 and 82 of the second and third floors. In addition, the channel 96 acts as a truss brace for the roof rafters and co-operates materially in trussing the parts and tying same against deflection in any and all directions.

65 70 75 From the foregoing, it will be noted, that many

of the construction elements are substantially under tensile strain, which is the ideal condition to have metallic members and thereby permitting the use of considerably lighter materials without the possibility of failure and thereby holding the cost of constructing the building or dwelling to a minimum.

75 80 85 It will be appreciated that if there were room partitions between the first and second floor beams or joists, the weight on the first floor beams or joists would be considerably supported by suspension from the above members, as above described, and may, therefore, be formed of lighter material than would be necessary if this weight were to be supported merely by the suspension of the beams or joists, even though an intermediate undersupport, such as 76, were or were not used, also, with this construction and the same weight of joist, a greater load could be carried.

90 95 100 It should be noted that there is no noise or squeaking in the flooring, after the same has been secured in position, due to the clamping of parts to one another and the absence of any movement of any metal to metal contacting parts. 105 This result is also obtained because the resilient nailing strips act as an insulator to sound, and very materially deaden any sound. It should also be noted in this connection, that the heretofore objectionable feature of reverberations, 110 found in rooms utilizing all metal beams or joists with metal lath and hard plaster, is eliminated, due to the fact that the metal lath is secured to the wood and not the metal. By comparison with the other types of composite structural elements, such as what are known as "bar joists," 115 the shrinkage in the nailing strips will have no bearing on the structure, since the nailing strip is held from the top, by the outer flooring, clamping the flanges of the metal side members between 120 said flooring and said nailing strip.

125 It is believed that, from the foregoing description, the other objects and advantages of the present invention, as initially pointed out, will be obtained, by using the construction element 130 previously described, and that the resulting building has the advantages of steel construction without losing the advantage of having the inside and outside facings, trim and the like, 135 expeditiously secured thereto, as by nailing, as 140 is the usual practice, and without the necessity of resorting to special connecting means, as is 145 the case with other metallic construction elements, now being employed.

150 155 What is claimed is:

1. In a construction element of the class described, the combination of a first side member formed of a sheet or strip of steel to provide a body portion having an exterior plane surface, and flanges projecting inwardly therefrom at 160 each edge of the body member and intermediate thereof, a second side member opposed to the first side member, and formed of a sheet or strip of steel and comprising a body portion having a plane exterior surface and a plurality of 165 flanges, projecting inwardly therefrom, one at each edge of the body portion and intermediate the edges thereof, the corresponding inwardly projecting flange of each side member lying in the same plane, whereby, between the edge 170 flanges and the adjacent intermediate flanges, a channel is provided, and a nailing strip in each channel.

175 2. In a construction element of the class described, the combination of a first side member

formed of a sheet or strip of steel to provide a body portion having an exterior plane surface, and flanges projecting inwardly therefrom at each edge of the body member and intermediate thereof, a second side member opposed to the first side member, and formed of a sheet or strip of steel and comprising a body portion having a plane exterior surface and a plurality of flanges, projecting inwardly therefrom, one at each edge of the body portion and intermediate the edges thereof, the corresponding inwardly projecting flange of each side member lying in the same plane, whereby, between the edge flanges and the adjacent intermediate flanges, a channel is provided, and a nailing strip in each channel, said side members each having spaced apertures in alignment with one another.

3. In a construction element of the class described, the combination of a first side member formed of a sheet or strip of steel to provide a body portion having an exterior plane surface, and flanges projecting inwardly therefrom at each edge of the body member and intermediate thereof, a second side member opposed to the first side member, and formed of a sheet or strip of steel and comprising a body portion having a plane exterior surface and a plurality of flanges, projecting inwardly therefrom, one at each edge of the body portion and intermediate the edges thereof, the corresponding inwardly projecting flange of each side member lying in the same plane, whereby, between the edge flanges and the adjacent intermediate flanges, a channel is provided, and a nailing strip in each channel, said side members each having spaced apertures in alignment with one another, means for connecting the opposed inner flanges of the side members to one another, and tie strips for connecting the edge flanges to one another.

4. In a construction element of the class described, the combination of a first side member formed of a sheet or strip of steel to provide a body portion having an exterior plane surface, and flanges projecting inwardly therefrom at each edge of the body member and intermediate thereof, a second side member opposed to the first side member, and formed of a sheet or strip of steel and comprising a body portion having a plane exterior surface and a plurality of flanges, projecting inwardly therefrom, one at each edge of the body portion and intermediate the edges thereof, the corresponding inwardly

projecting flange of each side member lying in the same plane, whereby, between the edge flanges and the adjacent intermediate flanges, a channel is provided, a nailing strip in each channel, and tie strips for connecting the edge flanges to one another.

5. In a construction element of the class described, the combination of a first side member formed of a sheet or strip of steel to provide a body portion having an exterior plane surface, and flanges projecting inwardly therefrom at each edge of the body member and intermediate thereof, a second side member opposed to the first side member, and formed of a sheet or strip of steel and comprising a body portion having a plane exterior surface and a plurality of flanges, projecting inwardly therefrom, one at each edge of the body portion and intermediate the edges thereof, the corresponding inwardly projecting flange of each side member lying in the same plane, whereby, between the edge flanges and the adjacent intermediate flanges, a channel is provided, a nailing strip in each channel, said side members each having spaced apertures in alignment with one another, means for connecting the opposed inner flanges of the side members to one another, and tie strips for connecting the edge flanges to one another.

6. In a building construction, the combination of a plurality of horizontal floor beams, each composed of metallic and resilient parts and together having a rectangular cross-section, providing substantially plane exterior surfaces with a nailing strip extending axially of one of said surfaces, a channel iron welded to the exterior surface of said beams, said channel comprising a perforated base and perforated, upturned flanges at the edges of said base, upright joists having one end disposed in said channel and formed of a metallic shell with plane surfaces and having a nailing strip extending axially of at least two of said surfaces, and means passing through the perforations of the channel into the upright nailing strips for securing same in position, a cap channel at the other ends of said upright joists having perforated base and flanges at the ends of the base, and means passing through the said perforations of the cap channels into the nailing strips of the upright.

AUGUSTINE DAVIS, JR. 50
